M. G. WILDER.
POWER PRESS.

No. 43.818.

Patented Aug. 9, 1864.

Inventor.
M. G. Wilder.

UNITED STATES PATENT OFFICE.

MOSES G. WILDER, OF MERIDEN, ASSIGNOR TO HIMSELF AND H. B. BIGELOW, OF NEW HAVEN, CONNECTICUT.

IMPROVED POWER-PRESS.

Specification forming part of Letters Patent No. 43,818, dated August 9, 1864.

To all whom it may concern:

Be it known that I, MOSES G. WILDER, of Meriden, in the county of New Haven and State of Connecticut, have invented new and useful Improvements in Power-Presses; and I do hereby declare the following to be a full, clear, and exact description of the construction and operation of the same, when taken in connection with the accompanying drawings and the letters of reference marked thereon, and which said drawings constitute part of this specification, and represent, in—

Figure 1, a front view; Fig. 2, a side view, and in Figs. 3 to 11, inclusive, detached views, to fully illustrate my improvements.

Similar letters and characters indicate corresponding parts in the several figures.

My invention relates to improvements in machines styled "power-presses," which are used for cutting, punching, &c., and in which the punches, cutters, &c., are fixed into a tool-holder or gate, which has a vertical movement given it by an eccentric to raise and force down the tool-holder; and it consists, first, in driving the gate or tool-holder by combining with an eccentric wrist formed on the driving-shaft, an eccentric roll fitted to the wrist so that the said roll may revolve freely thereon, both the roll and wrist of an equal eccentricity, so that when the roll and wrist are in opposition to each other the center of the roll coincides with that of the shaft, and, if permitted, will revolve with the shaft, consequently imparting no motion, but holds the gate or tool-holder at rest at its highest elevation, or, if the roll be held at its extreme or most distant eccentric radial point, so as to prevent its turning with the shaft, the throw of the eccentric wrist will be the same as without the roll, forming substantially the head of a pitman in which the wrist revolves, and as the point of holding the said roll is moved from the said extreme radial point to one less distant the throw of the wrist is diminished in like proportion as the radius is diminished, by which combination and arrangement the tool-holder, when at rest, always stands at its highest point or elevation, and the length of the throw may be diminished or increased; secondly, in the arrangement of a latch and lever to catch and release the eccentric roll

for the purpose of connecting and disconnecting the gate or tool-holder from the power, and by which arrangement the clutch, universally used and as universally condemned, is dispensed with; thirdly, in an adjustable friction-plate attached to the eccentric wrist and pressing upon the roll with sufficient force to and for the purpose of overcoming the friction of the roll within its strap which connects it to the pitman, so that when free it will revolve with the wrist within its strap concentric to the shaft, as before described.

To more fully illustrate my invention, I will describe its construction and operation.

A is the bed-plate; B, the frame or standard which supports in proper bearings the driving-shaft C, and also the gate or tool-holder D, which moves in proper guides, E E. Thus far the construction and arrangement are similar to common and well-known power-presses, the tools, dies, &c., inserted in like manner.

F is an eccentric wrist formed on the end of the driving-shaft C. (See Figs. 3 and 4.) On to the said wrist, and fitted so as to revolve freely thereon, I place an eccentric roll, I, of the same eccentricity as the wrist.

G is the pitman, its upper end forming the eccentric-strap *a*, and on its lower end a connecting-pin, II. (See Figs. 4 and 5.) Onto the gate or tool-holder D, I bolt or otherwise adjustably secure a cradle, K, (see Figs. 9 and 10,) in which a seat, *c*, is formed for the lower end of the pitman to work in, and also a link or box, *d*, into which the pin H sets for the purpose of lifting the gate. By raising the cradle and placing metal or other packing under it (as see *p*, Figs. 9 and 10) the gate may be lowered or raised in proportion as the packing is thicker or thinner.

f is a latch-bolt set in a groove formed in the pitman and forced up by a spiral spring, *g*.

L is a lever hung upon the top of the guide at *l*, and extends across the top and projects over the opposite side, which projection serves for a handle by which to move the lever. In Fig. 4 the said lever L is represented as moved back, and in Fig. 5 as moved forward. On the latch-bolt *f*, and near its upper end, I form a projection, *i*. (See Figs. 4 and 5.) When the lever L is moved back, as in Fig. 4, the

latch springs up into a notch, *n*, in the eccentric roll, and there holds the said roll to prevent its turning in the pitman. Thus it becomes as a part of the pitman, or the operation of the wrist is the same as it would be were the roll and pitman literally one piece. The driving-shaft being made to revolve while the eccentric roll is thus held, the eccentric wrist will force the pitman down, as in red, Fig. 3, and of course the gate with it to cut or punch, as may be, bring the lever *L* forward, as in Fig. 5, when, as the pitman ascends, the projection on the latch-bolt strikes the lever, which prevents it (the latch) from rising farther with the pitman, and consequently releases the eccentric roll, (as see Figs. 5 and 6.) In this position, released, the eccentric roll stands concentric with the driving-shaft, the friction-plate *o* on the wrist (which is a metal disk of larger diameter than the wrist, with one or more screws through it into the wrist to adjust its pressure upon the roll) presses on the eccentric roll with sufficient force to overcome the friction of the roll revolving in the strap. Consequently the wrist carries the roll with it, and in consequence of their equal eccentricity the roll simply revolves in the strap concentric to the shaft, (as see Fig. 6, where the wrist is represented in black and red at its two extremes in a revolution.) Consequently no movement is imparted to the slide, but it must rest always up—a great advantage over the ordinary press, where the slide may stop at any point within the limit of the eccentric, slip the lever back again, the latch springs up to the eccentric roll, and when the notch therein comes around the latch will spring into it and hold the roll as before. This said lever may be operated automatically by mech-

anism from the machine or by hand, or the foot of the operator.

As the movement of the pitman passing the dead-center is very slight vertically, so the horizontal movement of the pitman is greatest at these dead-points. To take advantage of these well-known facts, the upper end of the latch may be inclined, (as see Fig. 11,) and a corresponding incline formed on the lever, so that the side or horizontal movement of the pitman, as shown in red, Fig. 11, from right to left would tend to quicken the action, if not to entirely operate the latch to release the eccentric, which, in some cases, may be a great advantage.

I do not claim the combination of an eccentric roll and wrist-pin, as such combination is not new. Neither do I claim the combination of an eccentric roll and wrist-pin for the purpose of adjustment in power-presses, as such combination for adjustment is the invention of N. C. Stiles, of Meriden, Connecticut, as shown in a patent granted to him and dated January 26, 1864. Therefore,

Having thus fully described my invention, what I claim as new and useful, and desire to secure by Letters Patent, is—

1. The combination of the latch-bolt with an eccentric wrist and roll, when arranged to catch and release the roll, as and for the purpose specified.
2. The adjustable friction-plate described, in combination with the eccentric roll and wrist, for the purpose specified.

MOSES G. WILDER.
